DESIGN FOR A SLIP OR SIMILAR ARTICLE

Lucille Goold, New York, N. Y.

Application September 13, 1937, Serial No. 71,591

Term of patent 3½ years

To all whom it may concern:

Be it known that I, Lucille Goold, a citizen of the United States, residing in the city of New York, county of New York and State of New York, have invented a new, original, and ornamental Design for a Slip or Similar Article, of which the following is a specification, reference being had to the accompanying drawing, forming part thereof:

I claim:

The ornamental design for a slip or similar article substantially as shown.

LUCILLE GOOLD.
